STOCK QUOTATION MACHINE

Original Filed Sept. 25, 1931

UNITED STATES PATENT OFFICE

2,052,390

STOCK QUOTATION MACHINE

August D. Eitzen, Rockville Centre, N. Y., assignor to News Projection Corporation, New York, N. Y., a corporation of New York

Application September 25, 1931, Serial No. 565,085
Renewed January 9, 1935

14 Claims. (Cl. 178—42)

This invention relates to stock quotation projecting machines in general and more especially to stock quotation projecting machines associated with high speed motor driven tickers.

With the high speed motor driven tickers today in use, it is possible to produce the printing impression on the tape without interrupting the feeding operation. In view thereof, it is an object of the present invention to provide an improved stock quotation projecting machine associated with a high speed motor driven ticker in which the tape is continuously being advanced and as a result of which the last quotation printed before a period of rest, will be advanced into projecting position although the printing operation of the ticker may be interrupted for a greater or lesser period.

It is still another object of the present invention to provide an improved stock quotation projecting machine associated with a high speed motor driven ticker in which a rewind reel alone is depended upon for drawing the tape across the light aperture without the use of any independent tape puller, or tape movement control device.

It is still another object of the present invention to provide an improved stock quotation projecting machine in which little if any attention need be paid to the speed of the tape pulling motor other than to determine its speed to equal or exceed the speed of the tape as it is advanced to the light aperture by the ticker.

It is still another object of the present invention to provide an improved stock quotation projecting machine in which a high speed motor driven ticker may be converted into a continuously feeding device without affecting in any way any of the numerous actuating parts associated with the printer other than the actuating parts of the feed mechanism.

These and other features, capabilities and advantages of the invention will appear from the subjoined detail description of one specific embodiment thereof illustrated in the accompanying drawing in which

Figure 1 is a front elevation of a stock quotation projecting machine made according to the present invention;

Fig. 2 is a fragmental side elevation partly in section of the same;

Fig. 3 is an enlarged detail view showing the mechanism for actuating the feed roller used in the present invention; and

Fig. 4 is an enlarged end view of the mechanism shown in Fig. 3.

In the embodiment shown, the tape T passes

from the supply reel 1 of the ticker 2 mounted on the base 3 to the light aperture formed at the upper end of the extension 4 of the lamp housing 5 containing the lamp 6 from which the light rays pass through the lenses 7 and 8 to the deflector 9 by which they are deflected upwardly to the light aperture and the tape passing across the same to the objective lens contained in the housing 10 secured to the bracket 11 extending from the upper end of the extension 4. The light rays will then pass up to the deflector 12 from which they are deflected onto the deflector 13 from which they are in turn deflected onto the screen 14.

From the light aperture formed on the extension 4, the tape then passes down onto the rewind reel 15 mounted on the shaft 16 journaled in the bracket 17 on which there is mounted a pulley 18 which is connected by the spring belt 19 with the pulley 20 on the shaft 21 of the motor 22.

The ticker 2 in the present instance as illustrated, is a high speed motor driven ticker of the type recently adopted by the New York Stock Exchange, which is equipped with a motor 23 having a drive shaft 24 on which is mounted the motor pinion 25 in mesh with the type wheel shaft gear 26 and the main shaft gear 27 mounted on a shaft 28 on which is mounted the motor control pinion 29.

The gear 26 is mounted on the shaft 30 of the type wheel stop unit 31 at the end of which shaft is mounted the type wheel 32. The motor control pinion 29 meshes with the motor control gear 33 to which in the present instance the continuously operating tape feeding means are connected.

The tape feeding roller 34 in the high speed motor driven ticker heretofore in use was intermittently actuated. In the present instance, this intermittent actuating mechanism has been removed and the roller 34 mounted on the shaft 35 at the end of which is secured the beveled gear 36 in mesh with the beveled gear 37 at the lower end of the shaft 38, the upper end of which is provided with a beveled gear 39 in mesh with the beveled gear 40 on the horizontally extending shaft 41 at the end of which is mounted the driven gear 42 in mesh with the motor control gear 33 and as a result of which the feed roller 34 will be continuously operated when the ticker motor 23 is operating.

The roller 34 in the present instance is maintained in engagement with the tape T by the pressure roller 43 of standard construction.

mounted on the bracket 44 and urged into tape engaging position by the spring 45. The bracket 44 in the present instance is provided with the usual tape guide arm 46.

5 In operation, the speed of the rewind reel 15 at the start need only be determined to correspond with the tape advancing speed of the tape roller 34 since due to the increasing diameter of the tape roll on the rewind reel 15, the tape pulling speed will ordinarily tend to increase so that any slack that might be built up in the tape T due to the stretching of the tape would be quickly taken up as the diameter of the tape roll increased, or else the initial speed of the rewind reel 15 slightly exceeds the tape advancing speed of the tape feeding roller 34. The spring belt 19 will of course compensate for the excess of the speed of the rewind reel 15, if any, as compared to the tape advancing speed of the tape feeding roller 34.

From the foregoing, it will thus be seen that the rewind reel 15 will constantly maintain the tape T smoothed out at the light aperture and the movement of the tape across the light aperture be maintained uniform to correspond with the uniform tape feeding movement imparted to the tape by the tape feeding roller 34 and thus dispense with a uniformly operating tape pulling roller in addition to the rewind reel.

30 From the foregoing, it will also be seen that when the tape pulling motor 22 is started, it will tend to impart a rotative movement to the rewind reel which will slip in relation to the spring belt 19 so long as the ticker motor 23 is at rest, and that as soon as the ticker motor 23 starts operating, the tape feeding roller 34 will start its feeding action and continue to feed the tape T toward the light aperture in turn to permit the rewind reel 15 to take up the tape and draw it across the light aperture after so being discharged or advanced by the tape feeding roller 34.

35 In view of the foregoing, if a message is transmitted or a series of quotations are transmitted and the printer comes to rest the last quotation will continue to advance in the ordinary tape feeding period required to advance from the printing point to the light aperture and as a result of which the last quotations of a series located between the ticker and the light aperture will not be concealed from view any longer than the ordinary time required for them to advance from the printing point of the ticker to the light aperture.

40 From the foregoing, it would also appear that the standard high speed motor driven ticker can with facility be converted into a continuously feeding tape device without any reconstruction by merely the omission of the heretofore used intermittent tape feeding actuator and the replacement of the same with an actuating connection connecting the standard tape feeding roller 34 with the standard motor control gear 33.

45 It is obvious that various changes and modifications may be made to the details of construction without departing from the general spirit of the invention as set forth in the appended claims.

I claim:

50 1. The combination with a ticker having a continuous tape feeding device, of a tape drawing roller for drawing the tape from said continuous tape feeding device of said ticker, a continuously operating motor, and means for slippingly connecting said tape drawing roller to said motor.

55 2. The combination with a ticker having a con-

tinuous tape feed, of a continuously operating tape pulling device for drawing the tape from said continuous tape feed of said ticker.

3. The combination with a ticker having a continuous tape feeding device, of a rewind reel for drawing the tape as it is discharged by the tape feed of said ticker whereby a continuously taut stretch of tape is maintained between said continuous tape feeding device and said rewind reel.

4. A high speed motor driven ticker having a continuously operating motor, a printing mechanism, means for operatively connecting said printing mechanism to be operated by said motor in response to current impulses, a motor control gear continuously operated by said motor and independent of said printing mechanism, a tape feeding roller, and means for operatively connecting said motor control gear to said tape feeding roller to effect continuous operation of said tape feeding roller by said motor control gear.

5. The combination with a ticker having a continuously operating motor, a printing mechanism operatively connected to said motor, said printing mechanism including a selector for selecting the type to be actuated during printing operation by said motor in response to current impulses, a tape feeding roller, and means for drivingly connecting said tape feeding roller with said motor to be continuously rotated thereby.

6. The combination with a ticker having a motor, a continuously operating motor control gear, a continuously operating tape advancing roller, and means for drivingly connecting said motor control gear to said tape advancing roller, of a continuously operating tape drawing device for drawing the tape as it is advanced thereto by the tape feeding roller of the ticker.

7. The combination with a ticker having a motor, and a continuously driven tape feeding roller connected to said motor, of a continuously driven tape drawing device for drawing the tape as it is discharged by said tape feeding roller.

8. The combination with a ticker having a motor, and a continuously operating tape feeding roller drivingly connected to said motor, of a tape drawing device for drawing the tape as it is discharged by said tape feeding roller, a second motor continuously operating, and slippage means drivingly connecting said second motor to said tape drawing device to enable said tape to come to rest when said tape feeding roller comes to rest.

9. The combination with a motor operated ticker having a motor operable both when a message is transmitted and when a message is not transmitted by said ticker, and a continuously operating tape feeding roller drivingly connected to said motor, of a tape drawing device independent of said motor for drawing the tape as it is discharged by said tape feeding roller.

10. The combination with a motor operated ticker having a motor operable both when a message is transmitted and when a message is not transmitted by said ticker, and a tape feeding roller drivingly connected to said motor, of a continuously operating tape drawing device for drawing the tape as it is discharged by said tape feeding roller, a second motor continuously operating, and slippage means drivingly connecting said second motor to said tape drawing device to enable said tape to come to rest when said tape feeding roller comes to rest.

11. The combination of a ticker having a motor, a printing mechanism operatively con-

5 nected to said motor, said printing mechanism including a selector for selecting the type to be actuated during printing operation by said motor in response to current impulses, a tape feeding roller, and means for drivingly connecting said tape feeding roller with said motor to be rotated thereby independent of said printing mechanism.

10 12. The combination with a support, of a ticker having a motor operable both when a message is transmitted and when a message is not transmitted by said ticker, and a uniformly operating tape feeding roller in constant engagement with the tape between the printing location of the ticker and said support to prevent the transmission of vibrations to the tape at said support, and a tape moving roller independent of said roller for moving the tape across said support.

15 13. The combination with a support, of a ticker having a motor operable both when a message is transmitted and when a message is not transmitted by said ticker, a uniformly operating tape feeding roller drivingly connected to said motor and in constant engagement with the tape be-

tween the printing location of the ticker and said support to draw the tape out of the ticker, a tape moving roller cooperating with said tape feeding roller to draw the tape across said support and to maintain the movement of the tape uniform 5 while crossing said support, and a second motor independent of said first motor for driving said tape moving roller.

10 14. The combination with a support, of a ticker having a motor operable when a message is transmitted and when a message is not transmitted by said ticker, a uniformly operating tape feeding roller in constant engagement with the tape between the printing location of the ticker and said support to prevent the transmission of vibrations 15 to the tape at said support, a tape rewind reel for taking up the tape as it leaves said support and for cooperating with said feeding roller to maintain the movement of the tape uniform while crossing said support, a second continuously operating motor, and a slippage device for connecting said second motor to said rewind reel.

AUGUST D. EITZEN.
